TOY WAGON

Laverne O. Persinger and Merle L. Persinger, Burbank, Calif., assignors to Big Boy Manufacturing Co., Inc., Burbank, Calif., a corporation of California

Filed June 26, 1967, Ser. No. 7,594

Term of patent 14 years

(Cl. D34—15)

FIGURE 1 is a perspective view of a toy wagon showing our new design;

FIGURE 2 is a rear elevational view;

FIGURE 3 is a top plan view;

FIGURE 4 is a side elevational view showing the relationship of the tail wheel to the remainder of the wagon;

FIGURE 5 is a perspective view of a modified form of the toy wagon shown in FIGURE 1, wherein a rear skid bar is employed in lieu of the fifth wheel and the rear wheels are dualized;

FIGURE 6 is a rear elevational view thereof;

FIGURE 7 is a top plan view thereof; and

FIGURE 8 is a side elevational view showing the relationship of the tail skid to the remainder of the wagon.

We claim:

The ornamental design for a toy wagon, substantially as shown.
